MANUFACTURE OF ARTICLES FROM
POWDERED METALSGregory J. Comstock, Fairfield, Conn., assignor
to Handy & Harman, Bridgeport, Conn., a
corporation of New YorkNo Drawing. Application December 28, 1937,
Serial No. 182,162

17 Claims. (Cl. 41—23)

This invention relates to the manufacture of articles from powdered metals, and more particularly to the manufacture of ornamental objects, such as jewelry, silverware or objects of art in the form of mosaics.

This application is a continuation-in-part of my co-pending application Serial No. 35,631, filed August 10, 1935.

The invention is useful in the production of various ornamental objects, among which may be mentioned, by way of example, watch cases, vanity cases and cigarette cases, although it will be understood that the invention is applicable to many other uses. The mosaics of the present invention may be made of contrasting colors, forming a pattern which is very attractive, and which is permanent, even though the article is subjected to considerable wear. Mosaics made according to the present invention have a permanency which is not obtained by methods of surface ornamentation, such as plating or enameling, in which the pattern is destroyed after the surface has been worn off.

The mosaics of the present invention may be made from a variety of powdered metals, among which may be mentioned silver, gold, platinum, iridium, palladium, copper, nickel, zinc, antimony, cobalt, molybdenum, tungsten, titanium, tantalum, iron and alloys or combinations of these metals.

The invention will be described in connection with the production of a mosaic from silver and copper powders, it being understood that other combinations of metal powders or alloy powders may be employed. Silver powder is placed in a suitable mold and is presintered by the simultaneous application of heat and pressure, in order to form a presintered block which can be easily formed into pieces by sawing, filing, cutting or abrading. I may, for example, employ a pressure of approximately 500 to 1200 pounds per square inch and a temperature of 400 to 900° F., in order to produce the presintered block from the silver powder.

45. Powdered copper is also presintered by the simultaneous application of heat and pressure, to form a block of copper, which may be easily sawed or filed into smaller pieces. The presintered block of silver and the presintered block of copper are then cut into pieces of the desired size and shape and are assembled to form a mosaic of the pattern which is desired. The assembly is then placed in a mold and subjected to the simultaneous application of heat and

pressure. This consolidates the pieces and renders the product more dense.

The hot pressing of the assembled pieces form the mosaic is preferably carried employing a higher temperature and pressure than that employed in forming the presintered pieces. For example, the hot pressing of the assembled pieces may be carried out at a temperature of about 1300° F. and at a pressure of 3000 lbs. per square inch.

Various other metals may be employed in forming the presintered pieces, or alloys of metals may be used in forming the pieces. Where presintered pieces having contrasting colors are employed, very striking mosaics may be produced in the mosaic. Since the mosaic is not the result of surface ornamentation only but, on the contrary, the sintered pieces of different compositions extend entirely through the mosaic, it will have a long life, even when subjected to considerable wear.

In the preferred manner of practicing the invention as already described, the presintered pieces of silver and copper are formed by the hot pressing operation—that is, by subjecting the powdered metal to the simultaneous application of heat and pressure. Likewise after the presintered materials have been assembled to form the mosaic, they are preferably hot pressed. I may, however, form the presintered pieces by the cold press method, in which the powdered metal is compressed into a block while cold, the block is thereafter heated to a sintering temperature, either with or without the application of pressure.

Instead of hot pressing the pieces of presintered blocks which have been assembled to form a mosaic, I may simply heat the assembly without the use of pressure, to a temperature sufficient to consolidate the pieces together. An alternative, I may heat the assembled presintered pieces to a sintering temperature and then cool this by a pressing operation to consolidate the pieces together and render the mosaic dense.

In some cases, it is desirable to provide the mosaic with a backing, such as a metal plate. This backing may be a cast metal or alloy or may have been made by the sintering and pressing operations. In either case, when it is desired that the mosaic have a backing plate, the sintered pieces are arranged in the desired pattern on the backing plate and then the assembly, including the backing plate, is

not pressed or otherwise subjected to consolidate the presintered pieces and unite them to the backing

eed not be made up of presintered only. A part of the mosaic may t and rolled material and a part material made from powdered bodies are assembled to form the in the mosaic and then consolid or by heat and pressure in any of ously described, either with or ng.

ring operations may be carried out or steel or other mold connected circuit. I have used a high carbon steel mold with satisfactory reat may be communicated to the blocks of graphite or other suit the heater blocks being connected circuit. Where sintering is em the simultaneous application of rogen or other suitable furnace

owdered metals" as used in the ed to include powdered alloys or f metals.

ave described in detail the present er of practicing my invention, it stood that the invention may be died or practiced within the scope g claims.

od of making mosaics from pow which comprises forming a plu d bodies of different compositions eous application of heat and pres powdered metals, assembling the act with each other to form a bjecting the assembly to heat and

pressure sufficient to weld the contacting surfaces together and consolidate the sintered bodies into a continuous structure.

6. The method of making mosaics from powdered metals, which comprises forming a plurality of sintered bodies of different compositions by the simultaneous application of heat and pressure to the powdered metals, assembling the bodies in contact with each other to form a mosaic, and subjecting the assembly to the simultaneous application of heat and pressure sufficient to weld the contacting surfaces together and consolidate the sintered bodies into a continuous structure. 5

7. The method of making mosaics from powdered metals, which comprises forming a plurality of sintered bodies of different compositions and of a character to be easily workable by sawing, filing, cutting or abrading, dividing the bodies into pieces, assembling the pieces in contact with each other to form a mosaic, and heating the assembly to weld the contacting surfaces together and consolidate the pieces into a continuous structure. 10

8. The method of making mosaics from powdered metals, which comprises forming a plurality of sintered bodies of different compositions and of a character to be easily workable by sawing, filing, cutting or abrading, dividing the bodies into pieces, assembling the pieces in contact with each other to form a mosaic, and subjecting the assembly to the simultaneous application of heat and pressure to weld the contacting surfaces together and consolidate the pieces into a continuous structure. 25

9. The method of making mosaics from powdered metals, which comprises forming a plurality of sintered bodies of different compositions by the simultaneous application of heat and pressure to the powdered metals, the bodies being 40 easily workable by sawing, filing, cutting or abrading, dividing the bodies into pieces, assembling the pieces in contact with each other to form a mosaic, and subjecting the assembly to the simultaneous application of heat and pressure to weld the contacting surfaces together and consolidate the pieces into a continuous structure. 45

10. The method of making mosaics, which comprises assembling a plurality of preformed bodies of different compositions in contact with each 50 other to form a mosaic, at least a portion of said bodies being sintered and made from powdered metal, and heating the assembly to weld the contacting surfaces together and consolidate the bodies into a continuous structure. 55

11. The method of making mosaics, which comprises assembling a plurality of preformed bodies of different compositions in contact with each other to form a mosaic, at least a portion of said bodies being sintered and made from powdered metal, and subjecting the assembly to heat and pressure sufficient to weld the contacting surfaces together and consolidate the bodies into a continuous structure. 60

12. The method of making mosaics, which comprises assembling a plurality of preformed bodies of different compositions in contact with each other to form a mosaic, a portion of said bodies being sintered and made from powdered metal, another portion of said bodies being of cast metal, and subjecting the assembly to heat and pressure sufficient to weld the contacting surfaces together and consolidate the bodies into a continuous structure. 65

75

13. The method of making mosaics from powdered metals, which comprises forming a plurality of sintered bodies of different compositions, assembling the bodies on a backing in contact with each other to form a mosaic, and heating the assembly to weld the contacting surfaces together and consolidate the sintered bodies and backing into a continuous structure.
14. A mosaic comprising a plurality of sintered powdered metal bodies of different compositions, said bodies being welded to each other at their contacting surfaces and consolidated to form the mosaic.
15. A mosaic comprising a plurality of bodies of different compositions, at least a portion of said bodies being sintered powdered metal bodies, said bodies being welded to each other at their contacting surfaces and consolidated to form the mosaic and joined to a backing.
16. A mosaic comprising a plurality of sintered powdered metal bodies of different compositions, said bodies being welded to each other at their contacting surfaces and consolidated to form the mosaic and joined to a backing.
17. A mosaic comprising a plurality of bodies of different compositions, at least a portion of said bodies being sintered powdered metal bodies, said bodies being welded to each other at their contacting surfaces and consolidated to form the mosaic and joined to a backing.
